FIG. 1 is a perspective view of our new design for an orb pet water fountain;

FIG. 2 is a front elevation view thereof;

FIG. 3 is a back view thereof;

FIG. 4 is a right side view thereof;

FIG. 5 is a left side view thereof;

FIG. 6 is a top plan view thereof;

FIG. 7 is a bottom view thereof; and,

FIG. 8 is an exploded perspective view thereof.

The features shown in broken lines and portions contained within broken lines depict portions of the orb pet water fountain that form no part of the claimed design, and are not claimed.
